BRASSIÈRE GARMENT

Theo Belk Schaumer, Los Angeles, Calif.

Application June 7, 1947, Serial No. 753,225

5 Claims. (Cl. 2-42)

1

My invention has to do with brassière garments, having as an object the provision of a brassière so constructed as to conform to breasts of various sizes and characteristics. That is, prior brassière garments of which I am aware are so constructed as to make the breasts conform to the brassière, which often results in the garment being extremely uncomfortable and affording improper support.

Another object of my invention is to provide a brassière having a novel, highly efficient, reinforcing stitching arrangement—that is, a reinforcing stitching which is repeated for opposed portions of the garment in a plurality of parallel rows extending longitudinally of the body-encircling portion of the garment and around each cup, whereby to give additional support of the sides and back and to the biased cuts of the sides and back, keeping those portions of the garment from gapping and stretching and tending to mold the soft flesh of the wearer at the sides of the cups towards the front.

Another of the major objects of my invention resides in the novel construction of the body of the garment, which affords added support and effective uplift to the heavier portions of the breasts, minimizing the weight ordinarily suspended from the shoulder straps, and which enables the wearer, without discomfort, to wear the garment tighter than is ordinarily the case.

Another object of the invention is to provide a brassière construction which is conducive to improving the contour of the breasts.

A further object is the provision of a brassière construction which affords simplicity and economy of manufacture.

Still further objects and advantages of my invention will appear from the following description wherein I explain one presently preferred form of construction embodying the invention, making reference to the accompanying drawings illustrative of said construction, wherein:

Fig. 1 is a perspective of the completed garment;

Fig. 2 is a front elevation of the body portion of the garment;

Fig. 3 is a front elevational view of component parts from which each of the two upper cup portions of the garment is made;

Fig. 4 is an elevational view of the parts illustrated in Fig. 3 in assembled and stitched form; and

Fig. 5 is a section taken on line 5—5 of Fig. 1.

I wish it understood, however, that in its broader aspects as defined by the accompanying

2

claims, I do not intend to limit my invention to the specific details of construction now to be described, since it is capable of being carried out in other and modified structures without departing from its broader concept.

Referring now to the drawings, a brassière embodying my invention is shown as consisting of a body or lower portion B, upper cup and reinforcing portions C, shoulder straps D, and the connecting strip E.

In constructing my garment I first form the body portion B which consists of a strip of elasticized fabric, so elasticized that the stretch is principally in a direction longitudinally of the body. This body B has portions cut away along curved lines 5 providing recesses to receive the cups. The end portions B' of the body are somewhat triangular in shape; that is, although the bottom edge is substantially straight, the top edge tapers towards the end to provide a substantially pointed end. Between the recesses 5 the body has a relatively wide portion 7 having an inwardly curved top edge 8. The function and utility of this particular body construction will be hereinafter explained. Each of the two cup portions C is constructed by first cutting from a suitable fabric an upper member 10 having a side or underarm portion 11 which tapers to a point 12 at its outer end. A V-shaped dart is cut from the relatively larger inner end portion 16 leaving a V-shaped recess 15. Then two strips 17, 18 are cut, each being substantially triangular in shape except that the edges 17a, 17b, 17c, 18a, 18b, 18c are slightly outwardly curved. Then the recess 15 is closed by sewing its sides together, edge portions 17c, 18c of strips 17, 18 are sewed to the lower edge of the portion 16 and edge portions 17b, 18a are sewed together. This stitching or sewing provides an outwardly bulging or convexed cup for receiving and supporting the breast.

Next, a plurality of parallel reinforcing stitches 20 are provided in each of the members C, each of the stitches preferably extending longitudinally of the member and around the cup. The inner end of each stitch terminates at an angle to the top edge of the member. This stitching is repeated until each of the members C is covered with stitches 20 preferably spaced apart approximately $\frac{1}{16}$ of an inch, although this spacing may be varied. The completed element C may be described as each being comma-shaped.

Next, the elements C are sewed to the body B along their contiguous edges by stitching 22 and a pair of shoulder straps D are added if desired.

Each of the shoulder straps has a forked front end 25 secured to the top edge of the cup portion C and the back end of each strap is secured as by stitching to the end portion of the member C.

I find that by virtue of the combination of the elasticized body and relatively inelastic elements C the garment may be drawn tightly enough around the body of the wearer to afford adequate support without the use of shoulder straps being in all cases essential.

A connection strip E is then sewed at 27 to the end of one element C and carries a conventional hook fastener 28 at its outer end adapted to engage eyes 29 carried by the corresponding end of the other element C, to enable the garment to be secured in taut condition about the body of the wearer.

While I do not limit my invention to the particular sectional cup construction described, I find that construction to be conducive not only to economy of fabrication but also to provide most efficient and comfortable cup construction.

The stitching 20 which I have described not only gives unusual support to the cups but it also gives added support to the back and side portions since it closes the bias cut of the sides and back, keeping those portions of the garment from gapping and stretching and tending to mold the flesh around the cups at the side of the cups towards the front or apex of the cups. Particularly in conjunction with the elasticized body portion B is this stitching useful because the stressing caused by stretching the garment around the body of the wearer causes the brassière not only to conform to the breasts but also to provide ideal uplift and to cause the breasts and the soft flesh adjacent the breasts to be housed within the respective cups. The elasticized and relatively more yieldable body portion clings to the body and much of the weight of the busts which is ordinarily supported almost entirely from the shoulder in conventional brassières is supported by the body portion B, materially increasing the comfort of the garment. This is possible because the elasticized body portion permits a pull on both sides of the cup up past the heaviest part of the breasts. Also, the portion 7 of the elasticized body extending up between the cups affords the desired separation of the breasts and automatically conforms to the breasts of the wearer despite the fact that as between different wearers the breast separation varies considerably.

It will be observed that the portions B and C are so relatively arranged that the direction of pull exerted by the connecting strip E is at an angle to the disposition of the portion C, which exerts a stretching action on the body portion B in a manner tending to mold the breasts and surrounding soft flesh into the cups and to provide ideal uplift without discomfort.

I claim:

1. A brassière comprising a body-encircling member composed of an elastic strip having longitudinally spaced upwardly opening, substantially semi-circular recesses in its front portion, a substantially straight bottom edge and a top edge tapering from said respective recesses to its ends, and a pair of oppositely disposed relatively inelastic strips each having a cupped portion secured to the elastic strip around the edges of one of said recesses and a lateral extension secured along its bottom edge to a tapered top edge of the elastic strip and extending beyond the contiguous end of said elastic strip, and fastener means for securing the outer ends of said ex-

tensions together whereby to stretch the body-encircling member around the wearer's body and thereby to stress the elastic strip longitudinally.

2. A brassière comprising a body-encircling member composed of an elastic strip having longitudinally spaced upwardly opening, substantially semi-circular recesses in its front portion, a substantially straight bottom edge and a top edge tapering from said respective recesses to its ends, and a pair of oppositely disposed relatively inelastic strips each having a cupped portion secured to the elastic strip around the edges of one of said recesses and a lateral extension secured along its bottom edge to a tapered top edge of the elastic strip and extending beyond the contiguous end of said elastic strip, and fastener means for securing the outer ends of said extensions together whereby to stretch the body-encircling member around the wearer's body and thereby to stress the elastic strip longitudinally, each of said relatively inelastic strips having parallel reinforcing stitches extending parallel with its top edge, each of said stitches extending at its inner end portion circumferentially of the cupped portion.

3. In a brassière: a pair of spaced cup members; a body encircling member to which the cup members are attached; said body encircling member having ends projecting respectively away from the cup members; said ends being made from elastic material, and having a top edge and a bottom edge; and a pair of inelastic members attached respectively to the top edges of the ends, as well as to the upper outer portion of the cups; the lower edges of the ends being free.

4. In a brassière: a pair of domed cup members; a body encircling member attached to the bases of the cup members and extending below the cup members; the ends of the body encircling member projecting beyond the cup members and formed of elastic material; said ends having top edges leading, respectively, from the bases of the cups; and inelastic fabric material attached to the top edges of the said ends and also to the outer edge of the cup bases.

5. In a brassière: a pair of domed cup members; a body encircling member attached to the bases of the cup members and extending below the cup members; the ends of the body encircling member projecting beyond the cup members, and formed of elastic fabric material, and each having a concavity in its upper edge for attachment to the respective cup base, said concavity extending only partly along the outer edge of the respective cup; and inelastic members respectively attached to the top edges of said ends and to the cup members.

THEO BELK SCHAUMER.
